UNITED STATES PATENT OFFICE.

JAMES HIGGINS, OF CHICAGO, ILLINOIS.

IMPROVED MOSQUITO-BAR FRAME.

Specification forming part of Letters Patent No. 32,943, dated July 30, 1861.

To all whom it may concern:

Be it known that I, JAMES HIGGINS, of Chicago, in Cook county, in the State of Illinois, have invented a Portable Mosquito-Bar Frame, Room, or Tent; and I do hereby declare the following to be a full and exact description thereof, reference being had to the accompanying drawings, and the letters of reference marked thereon.

The nature of my invention is to construct and secure to each other by butts or hinges frames of wood or other material, so that when opened and covered with proper material it can be used as a protection against mosquitos and other winged insects, also that its construction is such that when not in use it can be folded up with its covering and placed out of the way.

A B C D is the main frame, of wood or other material.

s' t' n' p' is the wing-frame, attached to upright bar of main frame by butts or hinges and folding or swinging onto main frame.

s t n p is the wing-frame, attached to main frame like s' t' n' p' and folding onto main frame outside of wing-frame s' t' n' p'.

a b c d is the top frame, attached to top piece of main frame by butts or hinges and folding onto main frame outside of the wing-frames.

a' b' c' d' is the tent or roof frame, attached to top frame by butts or hinges and folding onto and outside of top frame.

xx is the prop to tent or hold up tent-frame.
r r r r are braces to strengthen and ornament the frame.

2 3 4 5 are casters on which to move the frame.

By folding together successively the wing, top, and tent frames, as indicated in the description, it will be evident by the small space that it occupies that it can readily be moved from one place to another and unfolded for immediate use.

When the frame is fitted with mosquito-bar cloth, it can be used in any part of a house or room to keep off mosquitos, flies, and other insects, over a bed to sleep under, over a table to eat or work under, or it can be taken into a garden or field and used for the same purposes. When covered with opaque cloth, it can be used as a room or office. When covered with cloth or other material that will keep out rain, it can be used as a tent. By attaching other wing and tent frames its shape and form may be varied as required.

What I claim is—

The combination and arrangement of the main frame with the two wing-frames and the top and tent frames, substantially as and for the purposes specified.

JAMES HIGGINS.
